UNITED STATES PATENT OFFICE.

ANDRÉ M. MERTZANOFF, OF NEW YORK, N. Y., ASSIGNOR TO AMERICAN RADIATOR COMPANY, OF CHICAGO, ILLINOIS, A CORPORATION OF NEW JERSEY.

HEATING APPARATUS.

Application filed January 20, 1919. Serial No. 272,019.

To all whom it may concern:

Be it known that I, ANDRÉ M. MERTZANOFF, a subject of the King of Greece, residing at the city of New York, borough of 5 Manhattan, county and State of New York, have invented certain new and useful Improvements in Heating Apparatus, of which the following is a full, clear, and exact specification.

10 My invention relates to improvements in heating apparatus, and the same has for its object, more particularly to provide a heating apparatus which may be located in rooms, and other parts of a building, and 15 supplied with a heating agent obtained from a central source.

Further, said invention has for its object, to provide a heating apparatus, having the general appearance of an ordinary steam or 20 hot water radiator, but in which the distribution or emission of heat by radiation will be substantially entirely suppressed.

Further, said invention has for its object, to provide a heating apparatus composed of 25 a series of connected elements or sections, adapted to receive a heating agent, and means for suppressing the radiant heat emitted thereby.

Further, said invention has for its object, 30 to provide a heating apparatus of sectional construction, adapted to receive a heating medium, and reflecting means surrounding or partly surrounding said heating apparatus whereby to suppress the radiant heat emitted 35 by said apparatus, and to increase or accelerate the convecting action of said apparatus.

Further, said invention has for its object to provide a heating apparatus of the character specified with means for preventing 40 the emitted radiant heat being absorbed by bodies in line therewith.

Other objects will in part be obvious and in part be pointed out hereinafter.

To the attainment of the aforesaid objects 45 and ends my invention consists in the novel details of construction, and in the combination, connection and arrangement of parts hereinafter more fully described and then pointed out in the claims.

50 Radiation, as is well known, is the transmission of heat through a medium commonly known as the ether, which is assumed to occupy all intermolecular spaces. Radiation always takes place in straight lines, obeying 55 the same laws as light, so that its intensity

or amount per unit of surface varies inversely as the square of the distance from the source of radiation to the surface, and directly with the line of the angle of inclination. Moreover, radiant heat continues to 60 travel in the same straight line until intercepted or absorbed by some other body.

The amount of radiant heat emitted or absorbed depends largely upon the character of the surface of the hot or cold body, and 65 it has been found that the power of a given substance for absorbing radiant heat is exactly the same as for emitting radiant heat.

Radiant heat, like light, is reflected from various materials, and it will be found that, 70 in general, substances possessing a high power of radiation have a low reflecting power. Silver has a relative radiating power of three but its reflecting power is 75 given as ninety-seven.

In general it may be said that the heat emitted by radiation per unit of surface and per unit of time is independent of the form and extent of the heated body, provided there are no re-entrant surfaces to intercept the heat rays. Also, the amount of heat emitted by a surface radiating equally in all directions depends only on the amount of surface, the nature of the surface, the difference in temperature between the surface and 80 surroundings, and the absolute value of the temperature.

To obtain the benefits and advantages of the physical laws above stated, I have constructed the heating apparatus as herein-after described in which radiation has been substantially wholly suppressed, first, by lowering the temperature of the exposed surface of the apparatus, second, by reducing the extent or amount of the exposed surface, 90 and, third, by the character or quality of the co-operating surfaces of the apparatus.

In the accompanying drawings forming part of this application and in which like numerals of reference refer to like parts:— 100

Figure 1 is a front elevation partly broken away, illustrating one form of heating apparatus constructed according to, and embodying my said invention;

Fig. 2 is a vertical section on line 2—2 of 105 Fig. 3, and

Fig. 3 is an enlarged detail top view, partly broken away.

In said drawing 10 designates the heating apparatus as a whole, comprising a heat- 110

emitting or radiating element formed of a plurality of individual, hollow metal sections 11, 11, resembling in a general way the sections of a radiator, and provided at their 5 upper and lower ends with tapped bosses 12, 12^a, respectively, to receive connecting nipples or couplings. The end sections, and, when necessary, one or more of the intermediate sections, may be provided with feet 10 13, 13, in order to support the structure as a whole in a slightly elevated position.

Each section 11 is provided along its opposite vertical edges, at both of its sides, with projecting ribs 14, which extend from 15 the top to the bottom thereof. The said ribs 14, 14 are adapted to register and contact with the corresponding ribs of the adjoining sections at each side, and are of such depth as to form a series of vertical air 20 passages 16 between the several assembled sections 11.

The lower and upper horizontal edges of the sections 11 are not provided with ribs, in order to form inlet and outlet openings 16^a and 16^b, respectively, leading to and from said air passages 16.

Each section 11 is preferably reduced transversely at its upper end so that the outlet openings 16^b shall be constricted.

30 The assembled sections are surrounded by a rectangular enclosure 17, which is supported in spaced relation to said radiator by bosses 18, preferably formed integrally with certain of said sections, and screws 19 35 passing through the walls of said enclosure 17 and into said bosses 18. The upper ends of the front and rear walls of said enclosure 17 are curved inwardly and upwardly to correspond generally to the curvature of the 40 reduced upper ends of the sections 11, and sufficiently spaced therefrom to form continuations of the air passages, 20, 20, formed between the outer sides of said sections, and the inner sides of the walls of the enclosure 45 17.

22 denotes an outer enclosing casing which is slightly larger than the enclosure 17 so as to provide air spaces 22^a between the outer side and top of said enclosure 17, 50 and the inner sides and top of said casing 22.

The casing 22 is provided in its front and rear walls adjacent to its bottom edges with apertured or perforated portions 23 serving as intakes for the air to be heated, and its 55 top 23', or in its side walls adjacent to its top, said casing is perforated or provided with apertures 24 to permit the air currents rising between the outer surfaces of the enclosure 17 and the inner wall of the casing 60 22 to pass therethrough.

26 denotes a plurality of longitudinal dampers or vanes which are pivotally supported at their opposite ends in bearings provided upon the under side of the top 23' of the casing 22, and connected together at

their corresponding ends by a link 27 having a finger portion 28 movable horizontally therewith, whereby said dampers may be jointly actuated to control or prevent the heated air currents which may issue from the 70 passages 16 between the sections 11, and the passages 20 between said sections and the enclosure 17, from passing out of the casing 22 and into the room in which the apparatus is located. While I have shown and described said controlling means as composed of a plurality of vanes, it will, of course, be understood that the same is merely one illustrative embodiment, and that any other suitable or convenient controlling means may 75 be employed.

When it is desired more effectively to prevent or to suppress the loss of heat by radiation from the radiator sections 11, the enclosure 17 may be made of a metal capable 80 of being highly polished, or of such other material as may be capable of being silvered, or of being coated, plated or otherwise provided with a substance which will convert the inner sides of the walls of said enclosure into a more efficient reflecting medium. By suppressing, to the utmost extent possible, all radiation, and confining within the enclosure 17 all heat emitted by the radiator, the convection action of the apparatus 85 will be increased to the maximum. The effect of rendering the apparatus more perfect as a convector results in an increased room heating efficiency of the apparatus, in that every particle of air contained in the 90 room is caused to pass through the apparatus, and become heated thereby. In this way it becomes possible to heat a room more rapidly and more effectively than is possible when the heating action is produced by radiation.

The operation of the apparatus is as follows:

The heating agent is supplied to the radiator sections 11 by the supply pipe 29, and after passing through the sections, it leaves through the return pipe 30. As soon as the radiator becomes heated, air from the room or chamber in which the apparatus is located will be drawn into the outer casing 22 through the intake opening in the grill or apertured portion 23, and thence pass upwardly in three separate currents; one current entering the inlet openings 16^a at the base of the radiator and passing through the passages 16 thereof and issuing through the constricted outer openings 16^b, a second current passing between the outer surfaces of the radiator 11 and the inner surfaces of the enclosure 16, and mingling at the upper constricted outlet thereof with the currents issuing through the constricted outlet openings 16^b of the radiator, and a third current passing between the outer surfaces of the enclosure 17 and the inner surfaces 125 130 135

of the casing 22 and issuing through the apertures 24 in the top 23' of said casing 22. The first and second mentioned currents of heated air passing through the central perforations 24 in the top 23' of the casing 22 may be controlled or arrested by opening the dampers 26 to a greater or less extent. The currents of air passing between the enclosure 17 and the casing 22, however, are not controlled but are permitted at all times to pass through the apertures 24 in the top 23' of the casing 22, and into the room or chamber.

By the particular construction and arrangement of the parts the air passing through the apparatus is caused to be divided into three separate currents, having different degrees of temperature and rates of travel, which progressively decrease in temperature and rate of flow as the same recede from the center of the apparatus toward the outermost wall. The outer wall is so spaced that its temperature will correspond substantially to that of the room and thereby eliminate radiation, that is to say, the hottest and most rapidly moving current is the center one which impinges directly upon or against the surfaces of the radiator or heat-emitting element, and the coolest and most slowly moving current is the one furthest removed from the radiator and nearest the parts of the apparatus which are in contact with the air at room temperature.

Having thus described my said invention, what I claim and desire to secure by Letters Patent is:—

1. An apparatus comprising a heat emitting-element having a plurality of independent air passages therein, a member surrounding said element and spaced therefrom to form an air passage, a housing enclosing said element and said member, and means for controlling the flow of air through the air passages in said element and the passages between said element and the member surrounding the same, substantially as specified.

2. An apparatus comprising a heat emitting-element having a plurality of independent air passages therein provided with constricted outlet openings, a member surrounding said element and spaced therefrom to form an air passage, a housing enclosing said element and said member, and means for controlling the flow of air through the air passages in said element and the passages between said element and the member surrounding the same, substantially as specified.

3. An apparatus comprising a heat emitting-element having a plurality of independent air passages therein provided with constricted outlet openings, a member surrounding said element and spaced therefrom

to form an air passage, a housing enclosing said element and said member, and a damper for controlling the flow of air through the air passages in said element and the passages between said element and the member surrounding the same, substantially as specified.

4. An apparatus comprising a heat emitting-element having a plurality of independent air passages therein provided with constricted outlet openings, a member surrounding said element and spaced therefrom to form an air passage, a housing enclosing said element and said member, and a damper for simultaneously controlling the flow of the several currents of air through the air passages in said element and the passages between said element and the member surrounding the same, substantially as specified.

5. An apparatus comprising a heat emitting-element having a plurality of air passages therein provided with constricted outlet openings, a member surrounding said element and spaced therefrom to form an air passage having a constricted outlet opening, a housing enclosing said element and said member, and valve means arranged in said member for controlling the flow of air through said element and through the passage between said element and the member surrounding the same, substantially as specified.

6. An apparatus comprising a heat-emitting element composed of a plurality of connected sections having peripheral flanges forming a plurality of air passages between said sections having constricted outlet openings, a member surrounding said element and spaced therefrom to form an air passage, a housing enclosing said element and said member, and means for controlling the flow of air through the air passages in said element, and the passage between said element and the member surrounding the same, substantially as specified.

7. An apparatus comprising a heat-emitting element composed of a plurality of constricted sections having peripheral flanges forming a plurality of air passages between said sections having connected outlet openings, a member surrounding said element and spaced therefrom to form an air passage having a constricted outlet opening therein, a housing enclosing said element and said member, and means for controlling the flow of air through the air passages in said element, and the passage between said element and the member surrounding the same, substantially as specified.

8. An apparatus of the character described comprising a heat-emitting element having a plurality of air passages extending therethrough and provided with con-

stricted outlets, a member surrounding said element and spaced therefrom to form an air passage, a housing enclosing said element and said member, and means to control 5 the flow of air through said air passage, substantially as specified.

9. An apparatus of the character described comprising a heat-emitting element having a plurality of air passages extending 10 therethrough, a casing surrounding said element in spaced relation thereto and provided with inlet and outlet openings, valve means for controlling said outlet openings and a second casing surrounding said first- 15 named casing in spaced relation thereto and provided with inlet and outlet openings, substantially as specified.

10. An apparatus of the character described comprising a heat emitting element 20 having open-ended air passages extending

therethrough, a constricted outlet communicating with said air passages, a plurality of casing members arranged in spaced relation to each other and to said heat emitting element and enclosing the latter; said inner casing having a constricted outlet into which the constricted outlet of said heat emitting member extends, and a valve in the constricted outlet of said inner casing member for controlling the passage of air through said 30 heat emitting member and said inner casing, substantially as specified.

Signed at the city of New York, in the county and State of New York, this 9th day of January, one thousand nine hundred 35 and nineteen.

ANDRÉ M. MERTZANOFF.
